UNITED STATES PATENT OFFICE.

HYMAN ELI GOLDBERG, OF CHICAGO, ILLINOIS.

AEROPLANE.

1,209,426.

Specification of Letters Patent. Patented Dec. 19, 1916.

Continuation of application Serial No. 692,269, filed April 22, 1912. This application filed April 15, 1916. Serial No. 91,289.

To all whom it may concern:

Be it known that I, HYMAN ELI GOLDBERG, a citizen of the United States, residing at Chicago, in the county of Cook and State of Illinois, have invented certain new and useful Improvements in Aeroplanes, of which the following is a specification.

One of the leading objects and salient features of the present invention is the production of a flying machine or aeroplane wherein the distribution of the masses is such as to effectually, materially, and automatically increase the stability of the appliance without employing equalizers, stabilizers, gyroscopes, rudders, or similar means.

Ordinarily little trouble is encountered by any displacement of a machine of this character so long as it does not cause any twisting or turning. It is of little consequence if a gust of wind blows an appliance of this kind some distance out of its true place or course so long as it does not effect any tipping or tilting of the device, because the aviator can bring it back readily into position. It is much more serious, however, if the displacement be angular instead of rectilinear, for under these circumstances, the flying machine may be very readily caused to point downward or upward. Assuming, therefore, that as a general rule right line movements are not dangerous, but that angular displacements are to be avoided, my invention is intended to materially increase the resistance of the appliance to any such sudden turning or twisting movements.

It has been the custom heretofore, to a large extent, among constructors of aeroplanes, to concentrate the mass of the machine, that is to say, the heavy parts thereof, such as the motor, the aviator, the tank, and the fuel contained therein, (the planes themselves being comparatively light), in one small comparatively compact place. This is a serious structural error and my invention in some of its embodiments consists in dividing and distributing the whole mass into a number of distinct portions or parts fairly widely distributed so that at these points there will be located considerable masses and at every other point in the appliance the mass will be as small as consistent with the required strength of the structure.

Generally speaking, one of the most con-

venient and desirable methods of distributing the mass of the appliance would be to place as nearly one-third as possible at each point or angle of a triangle, preferably, an equilateral triangle, although this is not vitally essential, since the triangle could conveniently be isosceles. Moreover, it is not absolutely essential that the mass at each vertex of the triangle be one-third of the total mass, the essence of the invention in its preferred embodiment residing in the distribution of the mass as a whole into a number of subsidiary masses as far from each other as practicable with comparatively little mass between them.

It is well understood that the resistance to angular displacement is proportional to the moment of inertia and that the latter is much larger for a distribution of masses such as has been described than for the same masses concentrated at one point. To illustrate by a concrete example, let us assume that each mass is a sphere of iron one ton in weight and that the three spheres are located at the vertices of an equilateral triangle ten feet on a side. Assuming also for simplicity that iron weighs five hundred pounds per cubic foot, it will be found that the moments of inertia of the three masses in the triangular arrangement are many times as great as the moments of inertia of the one concentrated mass. For instance, the moment of inertia of the three one-ton masses about an axis through the center of the triangle and perpendicular to the plane of the triangle is over forty times as great as the moment of inertia of the one three-ton mass about the same axis. The moment of inertia of the three one-ton masses about an axis in the plane of the triangle passing through their center of gravity and parallel to one of the sides of the triangle is over twenty times as great as the corresponding moment of inertia of the one three-ton mass. Again, the moment of inertia of the three one-ton masses about an axis in the plane of the triangle and perpendicular to one of the sides thereof and passing through their center of gravity is over twenty times as great as that of the one three-ton mass.

It being well known in mechanics that the moment of inertia about any axis is easily derivable from the moments of inertia about the three main axes of inertia and these having been given above, it will be

apparent that, under no circumstances will the moment of inertia of the three widely-separated one-ton masses be less than twenty times as great as the moment of inertia of 5 the one centralized three-ton mass. Obviously, the resistance to angular displacement will, under no circumstances, be less than twenty times as great, and possibly more. In the example noted, it has been assumed 10 that the three masses were located ten feet apart. This would constitute but a moderate sized aeroplane and a great many appliances of this character have been built much larger than that. It would not 15 be beyond the bounds of ordinary construction to locate the masses twenty feet apart, and in that case the moments of inertia of the three one-ton masses would be practically quadrupled. The resistance to angular 20 displacement in the larger triangular arrangement would, therefore, be not less than eighty times that of the one three-ton mass in any direction and many times more than that in other directions. In actual 25 practice one mass might be the motor, a second mass the aviator, and the third mass the tank and the fuel. The future development of aviation tending toward the use of two or more independent motors, so 30 that an accident to one will not completely cut off the power of the machine, in such cases, it might be more convenient to make two of the masses the two motors and the one or more aviators and the fuel the third 35 mass. In an aeroplane of this character it would be feasible and preferable to provide it with three distinct supporting planes, one for each of the masses, and quite close thereto, the whole structure being suitably 40 braced together, as will be readily understood. It is not necessary that each plane of the machine should be rigidly attached to the framing, but in some instances it would be desirable that it should be capable 45 of being either warped or tipped about an axis in order to apply the force for change of direction in a somewhat similar manner to each one of the masses.

A preferred embodiment of the invention 50 is illustrated in the accompanying drawing of which the figure presents a diagrammatic plan view of the flying machine or rather of the distribution of masses therein, and the location of the planes with respect to the 55 masses.

In view of the preceding description the drawing becomes practically self-explanatory, but it may be noted that in the application of the drawing each of the masses is 60 provided with the reference character 1 and each of the supporting planes associated therewith with the reference character 2, the bracing of the device being characterized 3. It will be seen that the planes 2 are 65 immediately adjacent to the masses 1 and

that the center of pressure of each supporting plane is very near the center of gravity of its corresponding mass. The distribution of the total mass into subsidiary masses located far apart as explained above, increases the moment of inertia, thus securing ample angular stability. The location of the centers of pressure of the planes in proximity to the centers of gravity of the masses permits the bracing members to be 70 short. This in turn produces a strong but 75 light construction of the whole machine.

In this preferred embodiment of the invention, I have illustrated and described 80 three subsidiary masses located at the vertices of an equilateral triangle, but it is to be understood that the invention is not limited to such a specific number of masses nor to that particular arrangement, the important point being to locate the whole mass as 85 far as is practicable from the total mass center regardless of the particular relative arrangement of the various portions of the total mass to obtain the desired large moment of inertia.

It may be observed that inasmuch as this 90 appliance does not depend for its angular stability upon the aeroplane members, but is conditioned upon the relation of the distributed load or mass to the total mass center, the resistance to angular displacement 95 of the structure is present just as much when the engine is not running as when it is operating. Furthermore, because this 100 appliance depends upon the distribution of the load into locally-concentrated masses spread around the total mass center at a substantial distance therefrom, the stability is not dependent upon the aeroplane members themselves, and so far as this invention 105 is concerned, it has just as much stability whether the planes are operative or so damaged as to become substantially valueless. A device incorporating this invention would 110 be just as effective against angular displacement in a vacuum as it is in the air and it consequently protects the aviator against the dangers of so-called air pockets.

Many minor mechanical changes may be 115 made in the appliance set forth herein without departure from the essential features of the invention as defined in the appended claims and without loss or sacrifice of its substantial benefits and advantages.

This application is a continuation of my 120 earlier application, Serial No. 692,269, filed April 22, 1912.

I claim:

1. An aeroplane wherein approximately 125 the total mass thereof including the load is distributed to surround the total mass center at a distance therefrom to thereby secure a large moment of inertia to resist angular displacement of the structure, substantially as described.

2. An aeroplane wherein approximately the total mass thereof including the load is divided into subsidiary locally-concentrated masses distributed around the total mass center at a distance therefrom to thereby secure a large moment of inertia to resist angular displacement of the structure, substantially as described.
3. An aeroplane wherein substantially the total load is divided into substantially equal subsidiary masses distributed to surround the total mass center at a distance therefrom to thereby secure a large moment of inertia to resist angular displacement of the structure, substantially as described.
4. An aeroplane constructed to resist angular displacement thereof wherein substantially the total load mass of the aeroplane is divided into three separate concentrated subsidiary masses located in triangular arrangement whereby to secure a relatively large moment of inertia, substantially as described.
5. An aeroplane constructed to resist angular displacement thereof, wherein substantially the total load mass of the aeroplane is divided into widely-separated, locally-concentrated, relatively-large subsidiary masses whereby to secure a large moment of inertia to resist angular displacement of the device, the lines joining the centers of such masses forming a convex polygon, substantially as described.
6. An aeroplane having a plurality of supporting-planes and having approximately its total load mass divided into the same number of parts as there are planes and distributed to surround the total mass center at a distance therefrom to secure a large moment of inertia to resist angular displacement of the structure, the center of pressure of each supporting plane being substantially vertically above the center of gravity of its corresponding mass, substantially as described.
7. An aeroplane having a plurality of supporting-planes and having substantially its total load divided into parts the number of which correspond to the number of the supporting-planes, said subsidiary masses being distributed around the total mass center at a distance therefrom to secure a large moment of inertia to resist angular displacement of the structure, the center of pressure of each supporting plane being near the center of gravity of its corresponding mass, substantially as described.
8. An aeroplane having three supporting-planes and having substantially the total load mass divided into three separate concentrated subsidiary masses located in triangular arrangement, whereby to secure a relatively large moment of inertia to resist angular displacement of the structure, the center of pressure of each plane and the center of gravity of its associate mass being approximately vertically one above the other, substantially as described.

HYMAN ELI GOLDBERG.
